CLAIM

The ornamental design for an auto-rack railroad car vehicle positioning device, as shown and described.

DESCRIPTION

FIG. 1 is a front perspective view of a auto-rack railroad car vehicle positioning device showing my new design;

FIG. 2 is a front elevation view;

FIG. 3 is a rear elevation view;

FIG. 4 is a top plan view

FIG. 5 is a bottom plan view; and,

FIG. 6 is a left side elevation view, the right side being a mirror image.

In the drawings, the broken lines in the Figures depict unclaimed subject matter only and form no part of the claimed design.
